UNITED STATES PATENT OFFICE

136,478

DESIGN FOR A RETAINER LIFTER BAR FOR A GRINDING MILL

Russell J. Williams, Chicago, Ill., assignor to
Kensington Steel Company, Chicago, Ill., a cor-
poration of Illinois

Application August 13, 1943, Serial No. 110,911

Term of patent 14 years

To all whom it may concern:

Be it known that I, Russell J. Williams, a citizen
of the United States of America, residing at
505 Kensington Avenue, Chicago, Illinois, have
invented a new, original, and ornamental Design
for a Retainer Lifter Bar for a Grinding Mill,
of which the following is a specification, refer-
ence being had to the accompanying drawing,
forming a part thereof.

Fig. 1 is an end elevational view of a retainer
lifter bar for a grinding mill embodying my new
design; Fig. 2 is a side elevational view; and Figs.
3 and 4 are bottom and top plan views respec-
tively of the same.

I claim:

The ornamental design for a retainer lifter bar
for a grinding mill, substantially as shown.

RUSSELL J. WILLIAMS.
